UNITED STATES PATENT OFFICE.

BEVERLEY RANDOLPH SCOTT, OF WOODLYNNE, NEW JERSEY, ASSIGNOR TO THE HAM-MARLUND MANUFACTURING COMPANY, INCORPORATED, A CORPORATION OF NEW YORK.

METHOD OF MAKING COILS.

Original application filed February 19, 1926, Serial No. 89,292. Divided and this application filed July 29, 1927. Serial No. 209,276.

My invention relates particularly to wire coils used for various purposes such as electric inductances.

One object is to provide a coil of high inductance value and low dielectric loss, relatively low resistance and small distributed capacity.

Another object is to provide a coil which can be readily handled and mounted.

10 Another object is to provide a coil having permanent and uniform characteristics.

I have solved the problem by the simple expedient of winding a coil upon a very thin layer of dielectric material such as celluloid to which it is permanently anchored by surface adhesion. The method of manufacture which will be hereinafter described is inexpensive and makes it possible to permanently maintain any desired spacing of 20 the various turns.

Fig. 1 is a side view of a coil made according to my invention.

Fig. 2 is an end view of the same.

25 Fig. 3 is a perspective view of a mandrel showing one method of applying the dielectric.

Figs. 4 and 5 are diagrammatic end views of two other arrangements of the supporting dielectric.

30 Fig. 6 is a diagrammatic end view of a coil of angular cross-section supported on two strips of dielectric.

Fig. 7 is an enlarged longitudinal sectional view showing a fragment of a coil in 35 process of manufacture.

Fig. 8 is a similar sectional view showing the same after the wire has been permanently secured in place.

The foundation 10 of the coil is made up 40 of one or more strips of a non-conducting material such as a nitro-cellulose composition, for instance, celluloid or pyroxylin, which is normally hard and not tacky or sticky at room temperature.

45 The conductor 11 is preferably covered with insulating material 12 such as silk or cotton fibre.

In making the coil I preferably employ a mandrel 13 made up of a series of sections 50 such as shown in Fig. 3 and provided with a tapered shaft 14 capable of supporting and expanding the mandrel.

According to the preferred method of manufacture, a very thin foundation sheet of celluloid, say five-thousandths of an inch 55 thick, is wrapped around the mandrel and the edges of the sheet overlapped, as indicated in Fig. 3, and stuck together by the simple expedient of applying a suitable solvent, such as ethyl-acetate, to the material 60 along the line of overlap, the edges of the sheet being drawn together smoothly and pressed together immediately after the solvent is applied. I have found that this operation of cementing the edges together can be greatly facilitated by the use of a sphincter spring 15. This spring normally rests in a groove 16 in one end of the mandrel and is run along the surface of the celluloid as soon as the overlapping edges have 70 been moistened with the solvent. Springs 16' hold the mandrel parts yieldingly together.

When the edges of the sheet have been 75 united on the mandrel the mandrel is expanded in the usual manner by simply driving the shaft longitudinally. This places the celluloid tube under tension and holds it smooth.

The mandrel is then placed in a winding 80 machine and the wire wound on it under tension. This tension should remain substantially constant throughout the winding operation and the feeding of the wire should of course be at the proper rate to lay the 85 wire with the desired spacing between adjacent turns.

When the coil has been wound, a suitable solvent, such as ethyl-acetate is applied to the foundation between the adjacent turns of 90 the wire, for instance, by means of a brush. This solvent also penetrates the insulation of the wire and immediately softens the surface of the foundation adjacent the wire.

The coil being under tension, as before described, of course tends to contract in diameter and its inner surface thus sinks slightly into the softened surface of the celluloid or the like. The change in condition before and after the application of the solvent is 95 shown by the difference between the relative positions of the coil and foundation as shown in Figs. 7 and 8.

The shaft may be retracted and the man-

drel contracted and withdrawn as soon as the material has substantially hardened, which requires only a few minutes. The finished coil will, however, continue to dry out for some time, the length of time varying with the composition of the material, the nature of the solvent and the amount applied, as well as the atmospheric conditions. In drying out the coil shrinks lengthwise, sometimes as much as 10%.

The coil may be wound at any length desired for special purposes. The method of manufacture lends itself particularly to the production of long tubes which can be very readily cut up into such lengths as may be desired which is much cheaper than the winding of small individual coils.

In the manufacture of these tubes, particularly in small diameters, there is sometimes a tendency for the tube to warp when made as above described, due to the overlapped joint along one edge. This can be readily avoided, however, by using two strips, such as 20 and 21, as shown in Fig. 4, so that there will be oppositely disposed joints which will offset each other in the shrinking process.

It should also be understood that a number of foundation strips may be used and that these strips may be spaced apart as shown for instance in Fig. 5. Here I have shown four strips 23 with spaces 24 between them, which form an open work or skeleton tube. A coil wound in this manner has an added advantage of reducing the dielectric material to a minimum. Such a coil having no overlapped joint has no tendency to warp in drying.

Although the coil is preferably circular in cross-section, it should be understood that certain features of the invention are applicable to coils of other cross-sections, for instance, in Fig. 6, I have shown a square coil wound on two separate strips 25 on opposite sides. This would, of course, leave the portions 26 of the wires on the intermediate sides of the coil spaced apart from each other without supports except at the edges of the strips 25. This requires much less of the foundation material.

Coils wound according to my invention may be used for various purposes, such, for instance, as radio frequency variable couplers, antenna couplers, interstage couplers, neutrodyne coils, short wave coils, etc. As they are very light in weight and self supporting they can be easily handled and mounted in various ways.

This is a division from my application #89,292 filed Feb. 19, 1926, in which I broadly claim a coil comprising a helix of conducting wire together with a sheet of insulating material touching and adhering to a surface of the helix throughout substantially the entire extent of the helix, the wire

making contact with the sheet on only a small segment of the circumference of the wire as herein set forth.

The coil wound on and self-cemented to a celluloid-like support is claimed in my divisional application #209,277 filed herewith.

I claim:

1. The method of making a coil which consists in securing a tube of celluloid-like material on a mandrel, winding insulated wire tightly thereon, then applying a solvent to the outer surface of the material between the turns of wire, thereby causing the wire to become partially embedded in the material and then allowing the material to dry. 80

2. The method of making a coil which comprises winding wire under tension onto thin celluloid, then applying solvent to the surface of the celluloid to soften it and allow the wire to become partially embedded and then allowing the celluloid to dry and the coil to shrink lengthwise. 85

3. The method of forming a wire coil which comprises forming a tube of material such as celluloid, applying pressure to the inside of the tube, winding turns of wire tightly on the tube, applying a solvent to the surface of the tube between the turns of wire and then removing the pressure from the tube and allowing the tube to dry. 90

4. The method of supporting wire which consists in placing insulated wire on a foundation of celluloid in spaced apart relation, applying solvent to the celluloid between the adjacent walls of the wire so as to cause the celluloid to impregnate the insulation and allowing the celluloid to set and adhere to the insulation. 100

5. The method of making a helical inductance coil comprising placing on a mandrel a band of insulating material having an insulating binding coating on the outer surface thereof, assembling the turns of said coil on said binding surface, hardening said binding surface after said winding is in place and then removing said mandrel after said binder has hardened. 105

6. The method of supporting wire which comprises laying the wire in spaced relation on a celluloid-like foundation, softening the foundation with a solvent such as ethyl-acetate between adjacent portions of the wire, allowing the wire to become slightly embedded in the foundation and then allowing the solvent to evaporate and the foundation to harden and adhere to the wire. 115

7. The method of forming a coil which comprises, first forming a tube of celluloid-like material by joining the edges of a sheet of such material, moistening one edge with a solvent and causing the edges to adhere to each other, then tightly winding wire on the tube, the adjacent turns of wire being spaced apart from each other, then applying a volatile solvent to the material between the turns 120

so as to soften the material and permit the wire to be slightly embedded in the softened surface of the material and then allowing the solvent to evaporate until the material sets 5 and holds the turns in place.

8. The method of securing together the turns of wire of a coil which consists in providing a support having an insulating binding substance at the outer surface thereof

10 which is hard at ordinary room temperature, arranging a coil on the support, softening the surface of the substance so as to allow the coil to sink slightly into the surface at the points of contact between the coil and the 15 surface, then hardening the binding substance.

9. The method of assembling an inductance coil on a support which consists in providing a support having a surface of celluloid, applying to the celluloid surface insu-

lated wire of the coil under pressure, treating the celluloid surface with a volatile solvent until the portion so treated has become soft enough adjacent the coil to allow the wire of the coil to sink into the softened 25 part, and subsequently allowing the solvent to evaporate and the celluloid support to set and adhere to a relatively small arc of the wire.

10. The method of forming a coil which 30 comprises forming a tube of material whose surface is capable of being softened, supporting said tube on the interior, stretching the material to hold it smooth, winding a conductor on said tube under tension, softening the surface of the tube immediately adjacent the conductor and allowing the material to harden. 35

BEVERLEY RANDOLPH SCOTT.
